ERNEST B. THURSTON, OF TOLEDO, OHIO, ASSIGNOR TO THE HAUGHTON ELEVATOR & MACHINE CO., OF TOLEDO, OHIO, A CORPORATION OF OHIO.

ELEVATOR-CONTROL SYSTEM.

Application filed May 8, 1922. Serial No. 559,172.

This invention relates to features of remote control for power equipment.

This invention has utility in connection with rotating field devices for operating switches for elevators and different features of acceleration such as multi-speed motor elevators. With three units as herein disclosed a two speed motor is controlled for operation in either of two directions at such two speeds with different acceleration for each speed.

Referring to the drawings:

Fig. 1 is a wiring diagram of the apparatus; and Fig. 2 is an across-the-line analysis of the control features of the devices, the reference characters in parenthesis indicating the operator for the switch adjacent which said parenthesis reference character is placed.

In a building or structure, elevator shaft 1 is shown as provided with landings 2, past which elevator car 3 may travel as carried by cable 4 about drum 5 thence over idler 6 to counterweight 7. Power for actuating this elevator car 3 is supplied by an alternating current motor 8 on shaft 9 having safety speed controller or flyball governor 10. Also on this shaft 9 is brake drum 11. This shaft 9 has worm 12 in mesh with worm wheel 13 on shaft 14 for effecting driving of the elevator car 3 through the drum 5 and the cable 4.

In the elevator car 3 is controller 15. Assuming the direction throw of the controller is for up direction of travel such may have the handle of the controller 15 thrown to the left. In the first position before such throw a contact 16 is connected with terminal 17 from which extends line 18 past car door interlock switch 19 and thence by line 20 to emergency switch 21. Line 22 from this switch 21 in the elevator car 3 extends to lower over-travel switch 23, thence by line 24 to upper over-travel switch 25, thence by line 26 to normally closed switch 27 as controlled by the speed governor 10. From this switch 27 extends line 28 to landing door interlocks 29, thence by line 30 to main power supply line 31.

Remote from the contact 16 this controller 15 has contact 32 in central or off position connected with terminal 33, from which extends line 34 to upper stop limit switch 35 to line 36 to the lower over-travel switch 23, thence by line 37 to the upper over-travel limit switch 25 to line 38 extending to main power supply line 39.

In shifting the controller 15 to the left for up direction travel of the car 3, the contact 16 comes to terminal 40 connected by line 41 to direction switch motor or rotating magnetic field magnet 42 where it connects with field winding 43. This winding 43 of a Y field winding is in communication with winding 44 from which extends line 45 connected to power supply line 51. For power supply to the brake there is branch from line 58 to resistance 46, thence by line 47 to coil 48 as an electromagnet winding, which as energized releases brake shoes 49 from the drum 11. These brake shoes 49 are normally held against the brake drum 11 by a compression spring. The circuit from this coil 48 extends by way of line 50 to power supply main line 51. Accordingly, at this first shifted position of the controller 15, one phase of current is supplied to the direction switch operating motor 42 and various safety devices as to the contact 16.

As controller 15 brings the contact 16 to the terminal 40, the contact 32 is brought to terminal 52 from which extends line 53 to winding 54 of the motor 42. This winding 54 is connected between the windings 43, 44. The direction switch 42 is accordingly energized for rotating shaft 55 carrying cam 56 effective for throwing up direction switch 57 to connect the power supply main line 31 with power supply line 58, extending through fixed resistance 59 to line 61 in communication with winding 62 of Y field winding for the motor 8. This up direction switch 57 in closing, also, connects an additional phase, for from the power supply line 39 there is connection to line 63 extending through interlock 64 on a high speed main switch control. This interlock 64 is closed at this period of starting from rest. From this interlock 64 extends line 65 to slow speed switch operating motor 66. This line 65 is in communication with Y field winding 67 of this motor 66. This winding 67 is connected through winding 68 with line 69 connected to the line 45. Between these windings 67, 68, this motor 66 has its third winding 70 connected to extend by way of line 71 to line 58 back of the direction switch.

The closing of the up direction switch 57 effects connection from the power supply line 39 to lines 63, 72, to resistance 73, thence by line 74 to second magnet coil 75 effective in

conjunction with the magnet coil 48 for releasing the brake shoes 49. This magnet coil 75 is connected to the line 50. The motor shaft 9 of the motor 8 is accordingly released as the direction motor 42 is energized and as the slow speed switch motor 66 is also energized.

This slow speed motor 66 has shaft 76 carrying pinion 77 in mesh with gear wheel 78 for two to one speed driving of shaft 79 carrying cam 80 operable for throwing in slow speed main switch 81, thereby connecting power line 82 from the line 63 with power line 83 extending to acceleration resistance 84, permanent resistance 85, thence by line 86 to field winding 87 of the motor 8 connected to the field winding 62. This closing of the slow speed main switch 81 also serves to connect power supply main line 51 with line 88 extending to acceleration resistance 89, permanent resistance 90, to line 91 connected to winding 92 as a field winding for the motor 8 connected between the windings 62, 87.

This throwing in of the main slow speed switch 81 occurs as soon as the slow speed switch operating motor 66 starts to operate. A slight interval thereafter cam 93 on this shaft 79 is effective for closing slow speed acceleration switch 94 serving to connect the line 83 with line 95 for cutting out resistance 84 and also connecting the line 88 with line 96 for cutting out acceleration resistance 89. Accordingly, at a brief time interval as determined by the positions of the cams 80, 93, on the shaft 79, there is a cutting out of the starting resistances 84, 89 from the windings 62, 87, 92, of the motor 8. This operation leaves permanent resistances 59, 85, 90, in the slow speed windings of this motor 8.

The permanent resistance in the low speed circuit is of utility as an automatic cushioning means when the motor is slowed down for stopping. This cushioning by the permanent resistance may be determined for the conditions of the job at the time of installation and is of special commercial value in adapting motors to such specific conditions.

Further shifting of the controller 15 from this slow speed operation toward high speed operation brings the contact 16 to terminal 97 in communication by way of line 98 extending to high speed switch operating motor of rotating field electromagnet 99. This line 98 extends to Y winding 100 connected with winding 101 extending to the line 45.

Simultaneously with the shifting of the contact 16 to the left, the lower contact 32 is shifted to the right to terminal 102 connected by way of line 103 to normally closed upper slow down switch 104. This switch 104 is located about ten or twelve feet short of the upper floor to which the elevator car 3 is allowed to travel. This distance depends upon the speed at which the car is intended to travel. This precludes running into the up-

per landing at high speed. From this upper slow down switch 104 extends line 105 to winding 106 at the motor 99.

This main high speed switch and high speed acceleration actuating device 99 has shaft 107 carrying pinion 108 in mesh with gear 109 for reduced speed driving of shaft 110. This speed reduction for these main high and high speed acceleration switches is two to one, as is the instance from the slow speed acceleration device 66. This shaft 110 carries cam 111 which, in the first period of operation of this operating device 99, is effective for throwing main high speed switch 112. This movement serves to shift switch 80 to de-energize the low speed switch operating motor 66 and automatically return such switch to off position. This throwing of the switch 112 is effective to connect the power line 63 from the direction switch 57 to line 113, to high speed winding 114 at the motor 8, and also connects the power line 51 through branch 115 to switch 112 and is there connected to line 116 extending to high speed winding 117 at the motor 8.

The up direction switch 57 thrown in connects the power line 31 to power line 58. From this power line 58 is branch power line 118 to high speed winding 119 at the motor 8. These high speed windings 114, 117, 119, at the motor 8 are in Y-form and the junction of the Y is brought out for the acceleration resistances. Line 119' from the winding 114 extends through resistances 120, 121, to the junction. Winding 117 has its line brought out by line 122 to acceleration resistances 123, 124. The third winding 114 has its connection brought out by way of line 125 through resistances 126, 127. These resistances in these windings 114, 117, 119, in high speed operation of the motor 8, are in communication through connection 128.

The continued operation of this operating device 99, right after the throwing of the cam 111 in closing the switch 112, causes cam 129 to throw switch 130. Between resistances 120, 121, is line 131 extending to the switch 130, while between resistance 123, 124, is line 132 also extending to the switch 130. Accordingly in this throwing of the switch 130 these lines 131, 132, are simultaneously connected by the line 133 between the resistances 126, 127. There is accordingly by this action an automatic cutting out of resistances 121, 124, 127, in the acceleration or starting of this motor 8 on this high speed.

A still further angle of travel effected by the driving device 99 of the shaft 110, in rolling the cam 134, operates switch 135 after the operation of the switch 130. This operation of the switch 135 serves to connect lines 119', 122, 125, so that the resistances 120, 123, and 126 are now cut out.

In the operation of the slow speed main switch and its acceleration cutout by the driv-

ing device 66 there is but one set of resistances cut out, while in this operation of the high speed driving device 99 there is not only throwing in of the main switch but two sets 5 of resistances are cut out.

In shifting the controller 15 for downward travel, it is thrown in a direction opposite to that heretofore described, and through such opposite throwing closes down direction 10 switch 143, with sequences of operation similar to those for upward travel.

When the elevator is travelling at high speed, if the controller 15 is moved to low speed position, the motor 99 will be de-energized and the shaft 110 will return by gravity 15 to its normal position. In doing so, the switches 135, 130 and 112 will be successively opened, thus cutting in the corresponding resistances before the high speed circuit is cut 20 out. In opening the switch 112, the switch interlock 64 will be closed, energizing the low speed circuit. Then, in sequence, the switch 81 is operable to cut out the resistances 84 and 89, leaving the permanent resistances 59, 85 25 and 90 in. Such a sequence of operation is especially desirable when stopping before the motor has reached its acceleration limit, as for example, in short travel distance from one floor to the next floor. Under such 30 conditions, there is still considerable torque in the motor when it is desired to stop the car. Cutting in of the resistances before the high speed switch opens, reduces the accelerating torque and prevents a jerk or bump when stopping.

35 The operator may, however, should he desire to do so, shift the controller from high speed in one direction to high speed in the other direction. Under such conditions, the current through the windings of the motor 42 will be reversed, and as soon as switch 57 is 40 closed, the switch 143 is opened, or vice versa, and the current through high speed windings of the motor 8 will be reversed.

In the operation of the shaft 110 for throwing 45 the plurality of switches, this shaft 110 carries disk 136 which has flexible connection 137 therefrom to weighted piston 138 reciprocable in dashpot 139 having leakage thereof adjustable by valve 140. Accordingly 50 there is possible an adjustment of the retarding action as well as gravity action of the counterweight for resetting these switches after the motor 99 is deenergized. In the operation of this motor 99 a limit for 55 travel is supplied by stop 141 carried by the disk 136 coacting with fixed stop or abutment 142. Similar stopping means is provided for the shaft 79 of the main slow speed and acceleration switches as operated by the device 66.

60 Similar resetting devices are accordingly provided for the slow speed main acceleration switches as provided for the high speed main and acceleration.

65 It is to be noted the construction herein disclosed is one of symmetrical and there-

fore substitutive form as to the form and elements of construction of the actuating devices for the switches and that as herein grouped there is a definite control of the speed of operation and the operation is quiet. 70

On the direction switch operating shaft 55 is cam 144, which in rotating in one direction may lift counterweight 145 and in the opposite direction may lift counterweight 146, which counterweights serve, on deenergizing 75 of the motor 42, for automatic resetting of the direction shaft.

It is further to be noted that the controller 15 is effective in one direction of operation for energizing motor 42 for one direction of 80 rotation while the opposite direction of throw of the controller 15 energizes the motor for reverse direction of travel. The remaining connections are such as to be used also for this motor 42, and should there be 85 on the line a reversal of phase a duplication of such reversal on the line does not bring about any confusion as to the control and car direction, nor as to the main and acceleration switch control sequences. It is also 90 apparent that if any phase of the current supply fails, due to a faulty connection, the controller will be rendered inoperative.

What is claimed and it is desired to secure by Letters Patent is: 95

1. In an electric elevator installation, multi-speed electric motor means, a starting device for the high speed circuit of said means, switches controlling said means, and switch operating devices constructed to reinsert 100 said starting device in the high speed circuit before said circuit is de-energized.

2. In an electric elevator installation, multi-speed electric motor means, a starting device for the high speed circuit of said means, switches controlling said means, switch operating devices constructed to reinsert 105 said starting device in the high speed circuit before said circuit is de-energized, and means whereby the high speed circuit may 110 be de-energized at the will of the operator without the reinsertion of the starting device.

3. In an electric elevator installation, an electric motor, main and direction 115 switches for controlling the motor, a starting device adapted to be inserted in the motor circuit when starting the motor, means for reinserting said starting device in said motor circuit before said circuit is de-energized, and means operable at the will of the operator to de-energize the motor circuit 120 without the reinsertion of said starting device.

4. In an electric elevator installation, 125 a polyphase multi-speed electric motor, polyphase primary windings therefor, a magnetic field energized by said windings, a starting device connected in one of the motor circuits, magnetic means controlling the operation of 130

the starting device, and means for actuating said magnetic means to reinsert the starting device in said motor circuit before said motor circuit is de-energized.

5. In an electric elevator installation, a multi-speed electric motor, a main switch therefor, an acceleration resistor connected with the high speed circuit, switches for said resistor, means for operating the resistor switches to cut down the resistance when starting, means operable to reinsert said resistor in the high speed circuit before said high speed circuit is de-energized, and means optionally operable to de-energize said high speed circuit without reinsertion of said resistor.

6. A control installation embodying power current supply conductors, acceleration switches, main and direction switches for cutting out the power current supply, said direction switches being operable for cutting out said supply in advance of opening of the acceleration switches, power devices for actuating said switches, one of said devices being connected for operating the main and acceleration switches, polyphase alternating current supply for the latter device, and a controller rendered inoperative by failure of a phase in said current supply.

7. A control installation embodying power current supply conductors, acceleration switches, main and directional switches for cutting out the power current supply, said direction switches being operable for cutting out said supply in advance of opening of the acceleration switches, power devices for actuating said switches, one of said devices being connected for operating the main and acceleration switches, polyphase alternating current supply for the latter device, a controller rendered inoperative by failure of a phase in said current supply, and resetting means for the main and accelerating switch operating device.

8. A control installation embodying power current supply conductors, acceleration switches, main and direction switches for cutting out the power current supply, said direction switches being operable for cutting out said supply in advance of opening of the acceleration switches, power devices for actuating said switches, one of said devices being connected for operating the main and acceleration switches, polyphase alternating current supply for the latter device, a controller rendered inoperative by failure of a phase in said current supply, and resetting means for the devices operable automatically.

9. A reversible motor, alternating electric current power supply therefor, acceleration means for the motor, acceleration switches for said acceleration means, main switches, reversing switch means for the motor, a rotating field device for the reversing switch means, an additional rotating field device

as a single mechanical operator for a group of said main and acceleration switches, and control mechanism for operating the latter device in different directions with different direction operation of the motor by said reversing switch means device.

10. An alternating current electric motor, low and high synchronous speed windings for the motor, direction switch means, acceleration means for the low synchronous speed winding, acceleration switches for said acceleration means, a main switch, a rotating field device for throwing said direction switch means, a second rotating field device as a single mechanical operator for thereafter throwing said main and acceleration switches, and control mechanism for one direction of operation of the latter device with one direction switch and the opposite direction of operation of the latter device with the other direction switch for controlling said acceleration switches for the acceleration means.

11. A control installation for a multi-speed alternating current electric motor embodying two rotating field magnet devices, a power line directly to both devices, a set of common axis rockable main and acceleration switches for each device, connections between said devices and switches for effecting operation of one set of switches by one device and the other set of said switches by the other device, two additional power lines, and control mechanism effective through said two additional lines for the second device whether or not the first device be thereby previously operated.

12. A control installation for a multi-speed alternating current electric motor embodying three rotating field magnet devices, a power line therefor directly to said three devices, direction switch means operable by one of said devices, low speed main and acceleration switches operable by a second device, high speed main and acceleration switches operable by a third device, two additional power lines for the devices, and control mechanism for reversing said two latter lines for reversing two of said devices.

13. An elevator control installation embodying a two speed motor provided with low and high speed windings, acceleration resistances for said windings in series therewith, two pole main and acceleration switches, a single mechanical power driven switch operator for a set of main and acceleration switches, and connections between the resistances and switches coacting for cutting out the resistance, said connections effecting through the successive operation of a plurality of said independent acceleration switches a balanced resistance cut out for the high speed acceleration.

14. An elevator control installation embodying a two speed motor provided with

- low and high speed **Y** windings, acceleration resistances for said windings in series therewith, two pole main, direction and acceleration switches, a single mechanical power driven switch operator, connections between the resistances and switches for permitting cutting out of the resistances, said connections effecting balanced cut out for the high speed acceleration resistances, and including means momentarily cutting in the resistances before opening said main switch.
15. A control installation for a two-speed alternating current motor, comprising direction switches, main and accelerating switches for each speed, a reversible rotating field magnet device for the direction switches, a second such magnet device for operating the main and acceleration switches for low speed, and a third such magnet device for operat-
- ing the main and acceleration switches for high speed, the actuation of said third device being effective to release said second device.
16. An elevator control installation embodying a two speed motor provided with high and low speed windings, acceleration resistance for said high speed windings, a high speed main switch, a low speed main switch, a direction switch, an acceleration resistance switch, a controller, and control connections for said switches which, when the controller is thrown from high speed to low speed position, momentarily cut in said acceleration resistance before opening said high speed main switch.

In witness whereof I affix my signature.

ERNEST B. THURSTON.
